UNITED STATES PATENT OFFICE.

ADAM COLLIS, OF ALTOONA, PENNSYLVANIA.

IMPROVEMENT IN PIPE-WRENCHES.

Specification forming part of Letters Patent No. **149,641**, dated April 14, 1874; application filed February 21, 1874.

To all whom it may concern:

Be it known that I, ADAM COLLIS, of Altoona, in the county of Blair and State of Pennsylvania, have invented a new and useful Improvement in Wrenches, of which the following is a specification:

This invention will first be fully described, and then pointed out in the claims.

In the accompanying drawing, Figure 1 is a side view of the wrench. Fig. 2 is an edge view of the same. Fig. 3 is a longitudinal section of Fig. 2, taken on the line *x x*.

Similar letters of reference indicate corresponding parts.

A is the head, which has a central hole, *B*, which allows it to be slipped over the stud which is to be turned. *C* is a projecting steel die in one side of the hole *B*. (See Fig. 1.) This die passes entirely through the head, and its edges are designed to penetrate the stud and prevent the wrench from turning on it. *D* is the working-lever. This lever works loosely in the head. Its end is ragged or serrated, and projects into the hole *B*, and engages with the bolt when the lever is drawn

toward the small screw *E*, as seen in dotted lines in Fig. 3. The end of the screw *E* enters a slot, *F*, in the lever, (see Fig. 3,) which allows it to play back and forth. *G* is a lip, which works through the side slot *H*. In gripping the bolt the lip *G* bears upon the side of the slot, by which a short and most powerful purchase is obtained to gripe the bolt, rod, or article to be turned. This is plainly seen in Fig. 3.

Having thus described my invention, I claim as new and desire to secure by Letters Patent—

1. A wrench constructed substantially as shown and described—that is, having a head with a fulerum lip and slot, substantially as seen at *G H*, and a working-lever, for the purposes described.

2. The head *A*, having screw *E*, in combination with the lever *D*, provided with slot *F*, for the purpose set forth.

ADAM COLLIS.
